HIGH FREQUENCY SIGNAL RESPONSIVE
CONTROL SYSTEMGeorge L. Beers, Haddonfield, N. J., assignor to
Radio Corporation of America, a corporation of
Delaware

Application March 31, 1937, Serial No. 134,105

11 Claims. (Cl. 250—20)

The present invention relates to a control system for radio receiving apparatus and the like, and more particularly to a control system responsive to received signals or oscillations, to provide controlling potentials which may be applied to the circuit elements of a radio receiving system or the like in effecting control of a predetermined portion, or a condition of operation of the system such as resonance indication, automatic frequency or gain control, automatic tuning, noise suppression or the like.

It is a primary object of the present invention, to provide a control system of the character above referred to, which provides a relatively large change in control potential for a relatively small change in the frequency of the applied signals or oscillations.

A further object of the present invention is to provide a control system for deriving a variable control potential, such as a biasing potential for radio tube circuits and the like, having a phase discriminating network in which a change in the frequency of applied signals or oscillations is converted into a difference in phase between two potentials normally having the same frequency.

It is also a further object of the present invention to provide a control system for radio receiving apparatus and the like, which provides a direct current control potential, the magnitude and polarity of which vary as the frequency of the applied signal varies from a predetermined value.

It is also an object of the invention, to provide a control system which is adapted to derive a variable direct current biasing potential, the magnitude and polarity of which vary as the frequency of an applied signal varies from a predetermined value, and which may be embodied in a radio receiving system in connection with existing circuits therein and without requiring the use of additional selective circuits.

It is also a further object of the present invention, to provide a control system for radio tube circuits and the like in which a phase discriminating network is adapted to provide a variable direct current biasing potential in response to a difference in phase between two voltages having the same frequency.

It is another object of the invention, to utilize in any of the control systems above referred to, a phase discriminating network which includes a pair of coupled tuned circuits, such as the primary and secondary of a conventional intermediate frequency transformer.

It is an object also, of the present invention,

to provide a control system for radio tubes, circuits and the like, responsive to differences in phase between two voltages having the same frequency, and having an output direct current potential adapted to provide electrical indications of the direction in which one of said voltages is differing from the other, in phase.

For the purpose of providing resonance indication and the like, it is a still further object of the present invention to provide a control system responsive to phase differences between two signals or oscillations having the same frequency, which provide an indication of one type at resonance, and an indication of another and different type at each side of resonance, preferably by a variation in the direct current output therefrom and reversal of polarity on either side of zero potential obtained at resonance.

The invention is also particularly adapted for use in connection with a superheterodyne type of radio receiver wherein the intermediate frequency amplifier provides coupled tuned circuits responsive to a predetermined intermediate frequency, which coupled tuned circuits may readily be included in a phase discriminating network and a control system embodying the invention.

The invention will, however, be better understood from the following description, when considered in connection with the accompanying drawings, and its scope will be pointed out in the appended claims.

In the drawings:

Figure 1 is a schematic circuit diagram of a control system embodying the invention.

Figure 2 is a further schematic circuit diagram of radio receiving apparatus and the like, provided with a control system embodying the invention.

Figure 3 is also a schematic circuit diagram of tuned high frequency radio tube apparatus provided with a control system embodying the invention, said control system being a modification of that shown in Figure 1.

Figure 4 is a graph indicating the response characteristic of the control system shown in Figure 2, and

Figure 5 is a graph showing curves illustrating the mode of operation of the control system of Figure 3.

Referring to Fig. 1, a double diode rectifier device 5 having a cathode 6 and diode anode elements 7 and 8, is provided as a preferred form of rectifier. The anode elements are connected to the opposite ends or terminals 9 and 10 of a tuned high frequency signal circuit 11 comprising

ing a two-section inductance, indicated at 12 and 13, and a shunt variable tuning capacitor 14.

Two series connected resistor elements 15 and 16 are connected between the two sections of the inductance, in series therewith. These resistors are provided with two outer terminals 17 and 18 and a center tap 19, the latter being connected through a second tuned circuit 20 with the cathode 6 of the rectifier device.

- 10 The tuned circuit 20 comprises a second inductance or winding 21 and a shunt variable tuning capacitor 22 therefor. The circuit 20 is preferably tunable through the same frequency range or to the same resonance frequency as the 15 circuit 11.

16 The resistors 15 and 16 are provided with bypass capacitors 23 and 24, respectively, and the terminals 17 and 18 are provided with output leads 25 and 26, respectively, for applying control potentials derived from the resistors 15 and 16, to any suitable control system in a radio receiver or like apparatus. The adaptability of the derived potentials for control purposes is indicated in the following consideration of the characteristics of such potentials and operation of the control network.

With the control network in a tuned signal circuit, if a voltmeter or other voltage indication device 27 is connected between the control 30 or output leads 25 and 26, and if the device is responsive to applied voltages to show a deflection or indication in either direction from a center or zero deflection, as shown, whereby it will indicate positive and negative polarities without reversal of the lead connections therewith, the meter 27 will show a zero deflection at resonance to an incoming signal, a deflection in one direction for tuning adjustment below resonance to said incoming signal, and deflection in the opposite direction for tuning adjustment above resonance. The reason for this will be seen from the following analysis of the operation.

If high frequency energy is applied to the tuned circuit 11 only, the voltage developed therein will be applied to the terminals 9 and 10 and to the anodes 7 and 8 of the rectifier device 5. The potentials on the anodes 7 and 8, as supplied by the tuned circuit 11, will be 180° out of phase. The current rectified by the section of the double diode including the anode 7 and the cathode 6 will flow from the anode 7 to the cathode 6 thence through the winding 21 of the tuned circuit 20, to the terminal 19, then through the resistor section 15 and the inductance section 12, to the terminal 9 and the anode 7. The current flowing through resistor 15 will be in such a direction to cause terminal 17 to become more negative with respect to the terminal 19.

The current rectified by the section of the double diode including the anode 8 and the cathode 6, will flow from the anode 8 to the cathode 6, through the winding 21 of the tuned circuit 20, to the terminal 19, through the resistor section 16 and the inductance section 13, to the terminal 10 and the anode 8. Thus it will be seen that a voltage induced in the tuned circuit 11 from any suitable source, will cause a current to flow through the resistor 16 in such a direction to make the terminal 18 more negative with respect to the terminal 19, in the same manner that the terminal 17 is made more negative than the terminal 19.

Thus, if the inductance sections are equal, equal radio frequency voltages will be developed thereacross and the voltages developed across

resistors 15 and 16 due to the rectified current flowing therethrough will be equal and opposite in polarity, if the resistors 15 and 16 have equal resistance values. Therefore, a voltage induced into the tuned circuit 11 will not cause a difference of potential to exist between the resistor output terminals 17 and 18.

If a voltage is induced only into the tuned circuit 20, it will be seen that it will be applied to the anode elements 7 and 8 in phase. This voltage will likewise cause equal rectified currents to flow through resistors 15 and 16 and in opposite directions from the center terminal 19, such that the voltages developed across the resistors are in opposition and that again, no difference 15 in potential will exist between the terminals 17 and 18.

Therefore, if a signal or high frequency voltage is applied to the diode rectifier by the tuned circuit 11, the differential potential or net voltage 20 developed across the output terminals 17 and 18 will be substantially zero. The same condition is provided if a signal or high frequency voltage is applied to the diode rectifier elements through only the tuned circuit 20.

Assuming now, that a high frequency signal is supplied to the diode rectifier through both tuned circuits and the voltage applied to the anode element 7 by the tuned circuit 11 is in phase with that supplied by the circuit 20, the voltages will 30 add and a large current will flow through the resistor 15. The voltages on the anode 8 connected to the terminal 10 are then out of phase and if they are equal these voltages will cancel and no current will flow through the resistor 16. 35 The differential voltage then appearing across the resistor combination 15 and 16 at the output leads 25 and 26 or the terminals 17 and 18 will be such that the terminal 17 will be negative with respect to terminal 18. If the terminal 19 is connected to ground, as indicated at 28, the lead 25 will be negative with respect to ground while the lead 26 will be substantially at ground potential.

If the phase of the voltage supplied to either tuned circuit is now shifted by 180°, the large current will flow through the resistor 16. In this case, the voltage appearing across the output terminals 17 and 18 and the leads 25 and 26 will be such that the terminal 18 will be negative with respect to the terminal 17.

If the phase of the voltage obtained from the tuned circuit 20 differs by 90° from that supplied by the tuned circuit 11 the current flowing through the output resistor 16 will be equal and opposite to that flowing in the output resistor 55 15 and no voltage will be obtained at the terminals 17 and 18 or the output leads 25 and 26.

Thus it will be seen, that as the phase difference in the voltages supplied by the tuned circuits 11 and 20 is varied through 180°, the voltage across the output terminals or leads of the resistor network will decrease in magnitude, will pass through zero and will then change direction and increase until it attains the original magnitude in the opposite direction. If the phase 65 relation between the voltages introduced by the two tuned circuits is so arranged that a phase difference of 90° exists at resonance, then the system will not only indicate resonance, but will also indicate on which side of resonance the applied 70 signal is tuned as the tuning is varied.

Thus it has been shown that by employing a phase discriminating network such as that illustrated in Fig. 1, a control potential can be derived which varies both in magnitude and polarity 75

as the phase relation between two high frequency voltages is varied.

Several means (which can readily be incorporated in a radio receiving system) have been devised for obtaining the desired variation in phase relation between two signal voltages.

For example, I have found that if a received signal is passed through two portions of a receiving system, one of which has a selectivity characteristic such as illustrated by curve ABC in Fig. 4, and the other of which has a selectivity characteristic represented by curve DBE in the same figure, that the phase relation between the two voltages representing the signal output of these two portions of the receiving system, will vary through approximately 180° as the frequency of the applied signal is varied. If the signal voltage applied to the input circuits of the two portions of the receiver are in phase and if the difference in the number of coupled tuned circuit amplifier stages in the two portions of the receiver is an odd number, then the output voltages of the two signal channels will be 90° out of phase at resonance.

This arrangement will best be understood by reference to Fig. 2 of the drawings, wherein the rectangle 30 represents any suitable radio receiving system having tuning means indicated by the tuned circuit 32 and variable tuning capacitor 33, and means provided by an input winding 34 for applying thereto oscillations or signals from any suitable source, such as an antenna circuit 35.

A high or intermediate frequency output circuit for the receiving system is indicated at 35 and includes a coupling transformer having a tuned primary winding 37 coupled to a secondary winding comprising two substantially equal inductance sections 38 and 39. The secondary sections are connected in series at their inner or adjacent ends through two resistors 40 and 41, and at the opposite or outer ends are connected with a shunt tuning capacitor 42 and the anode electrodes 43 and 44 of a double diode rectifier 49, the common cathode of which is indicated at 45.

The resistors 40 and 41 are provided with shunt bypass capacitors 46 and 47, and the center tap indicated at 48 between the resistors is connected to the cathode 45 through a tuned secondary winding 50 of a second coupling transformer 54. The transformer 54 is provided with a tuned primary winding 51 which is connected to a suitable two-way switch having movable contact elements 60 and 61, and fixed contacts 62, 63 and 64, 65.

The grid of an amplifier tube 68 is coupled to the anode end of the inductance 38 by means of a coupling capacitor 66. Grid bias potential is provided through a resistor 67 and a self bias resistor 69. The anode of this tube is connected to the switch contact 63. When the switch elements 60 and 61 are connected with the contacts 63 and 65, the tuned primary which includes the inductance 51 and the variable capacitor 53, is connected in the plate circuit of tube 68. Signal potential appearing across the tuned circuit, which includes the inductances 38 and 39, is impressed on the anodes 43 and 44, 180° out of phase, and on the grid of tube 68, in phase with the potential on the anode 43. The signal output of the tube 68 is impressed on the anodes 43 and 44 of the double diode rectifier 49 through the coupled tuned circuit transformer 54. Since the voltage on the grid of the tube 68 is in phase

with that impressed on the anode 43 from the tuned secondary circuit, which includes the secondary inductances 38 and 39 of the transformer 36, the voltage developed across the secondary 50 of the transformer 54 is 90° out of phase with the voltage across the secondary of transformer 36, when these two transformers are adjusted to resonance with the received signal.

Thus a received signal at the resonance frequency of the transformers 36 and 54, causes two voltages at the same frequency to be applied to the double diode 45, one of which voltages is 90° out of phase with the other. As the frequency of the received signal is varied slightly, or if the tuning of the receiver is varied slightly, the phase relation between the two voltages will vary through a range of approximately 180° . As this change in the phase relation between the two voltages occurs, the voltage across resistors 40 and 41 will vary in the manner previously described.

Thus the voltage across this resistor combination will decrease from a given negative value, pass through zero, and then increase until it reaches a positive value comparable to the initial negative value as the receiver is tuned from one side of the receiver resonance characteristic to the other.

This same variation in the potential developed across the resistor combination 40-41 will occur if a signal from a local oscillator, illustrated by the block 52, is applied to the transformer 50 by connecting the switch contact members 60 and 61 to the contacts 62 and 64 respectively. Thus, if the oscillator 52 is arranged to provide oscillations at 175 k. c., for example, and the output circuit 36 of the receiver is also an intermediate frequency circuit tuned to 175 k. c., when the oscillator potential impressed on the anode 43 is in phase with the received signal, it will be out of phase with the signal on the anode 44. Under this condition, the maximum current will flow through resistor 40 and no current will flow through resistor 41. If the received signal potential is reversed in phase by 180° , then a current will flow through resistor 41 and no current will flow through resistor 40.

If the phase difference between the received signal and the local oscillator potential on the anode of the double diode rectifier is 90° , then equal currents will flow in resistors 40 and 41. Since these currents flow in opposite directions from the anode connection at the terminal 48, by reason of the rectifier action, the voltage at the outer end terminals 55 and 56 of the resistor combination will be zero, since the total voltage drop across the two resistors will be zero.

Thus, the direction and magnitude of the voltage developed across the resistor combination 40 and 41, connected in the center of the secondary winding, is a function of the phase relation between the received signal or intermediate frequency voltage and the local oscillator voltage provided by the source 52. The receiver circuits are so arranged that when the receiver is tuned to resonance, the carrier wave or intermediate frequency signal as applied to the rectifier 49, is 90° out of phase with the oscillator voltage, whereby the direct current biasing potentials across terminals 55 and 56 are zero.

The direct current control or bias potential developed across the resistor combination 40-41 may then vary in either direction in accordance with variation of the tuning from resonance, and the potential developed at the terminals 55 and 56

and 56 may be utilized to control the tube circuits of the receiver 30 in any suitable manner. As the frequency of the received signal tends to vary from that provided by the oscillator, the phase shift caused thereby disturbs the balance in potential drop between the resistors 40 and 41, and a corresponding change in bias or control potential at the terminals 55 and 56 may be applied to the receiving system 30 through suitable control leads 57.

Another modification which I have found to be very satisfactory for applying the two alternating current voltages to the phase discriminating network is to make use of the voltage across both the primary and secondary of a coupled tuned circuit transformer.

Referring to Fig. 3, a portion of an intermediate frequency amplifier circuit is shown, comprising an intermediate frequency amplifier tube 70 connected with an intermediate frequency input transformer 71 and having an output circuit 72 coupled to the primary winding 73 of a second intermediate frequency coupling transformer 36a. The secondary is divided into two equal winding sections 74 and 75, whereby it is adapted to be connected into a phase discriminating network of the type shown in the preceding figures, for deriving control potentials through a diode rectifier device 76.

In this circuit, however, the diode rectifier anodes, indicated at 77 and 78, are connected with the end terminals of the secondary which is tuned by a suitable shunt tuning capacitor 79, but the potential applied between the cathode indicated at 80, and the center tap 81 of the output resistors 82 and 83 is derived from the high potential terminal 84 of the primary or input circuit 85, the connection being made between the cathode 80 and the high potential terminal 84 through a lead 86. The opposite side of the tuned primary winding is connected to ground as indicated at 87. Likewise the center tap 81 is connected to ground as indicated at 88. Direct current control potentials are derived from the resistor output terminals 89 and 90 through output leads indicated at 91 and 92.

In this circuit, advantage is taken of the fact that at resonance the primary and secondary voltages, of the coupled tuned circuit intermediate frequency transformer 36a, are 90° out of phase with each other. By applying the voltage across the primary of the transformer between the cathode 80 and the resistor center tap 81, and the secondary voltage between the two diode anodes 77 and 78, the desired phase relations for the phase discriminating network are obtained. If the frequency of the signal applied to the transformer is changed either because of a slight change in the tuning of the receiver, or a change in the frequency of the transmitter, the phase relation between the primary and secondary voltages will change. A phase change of approximately 180° will be obtained between the primary and secondary voltages as the frequency of the signal applied to the transformer is varied through the frequency range included within the resonance characteristic of the transformer 36a.

When the signal applied to the intermediate frequency amplifier tube 70 is in resonance with the transformer feeding the double diode rectifier 76, a voltage will be applied between the cathode 80 and the resistor center tap 81 which will be 90° out of phase with the voltage developed across the secondary coil sections 74 and 75 and applied between the anodes 77 and 78.

If only the voltage developed across the transformer primary is applied to the double diode between the cathode 80 and the resistor center tap 81, the rectified current flowing through the resistor section 82 will be equal and opposite in direction to that flowing through resistor section 83 and the voltage between the terminals 89 and 90 will be zero. Likewise if only the voltage developed across the secondary of the transformer is applied to the double diode rectifier between the anodes 77 and 78, the rectified current flowing through the resistor section 82 will be equal and opposite in direction to that flowing through resistor section 83 and the voltage between the terminals 89 and 90 will be zero.

If both the primary and secondary voltages are applied to the double diode and these voltages are 90° out of phase, as will be obtained if the signal applied to the transformer has the frequency to which the transformer is resonant, then the signal voltages applied to the two anodes will still be equal and the rectified currents flowing through the two resistor sections will be equal and opposite and the voltage between terminals 89 and 90 will be zero.

If, however, the signal potential applied to the transformer has a frequency which differs slightly from the resonance frequency of the transformer, the phase relation between the primary and secondary voltages will no longer be 90° and the signal potentials applied to the two anodes will not be equal and a difference in potential will exist between the terminals 89 and 90 because the rectified currents flowing through resistor sections 82 and 83 will be unequal.

Let us assume for example that the applied signal has a frequency which is just inside the frequency response characteristic of the transformer. With a conventional intermediate frequency transformer this signal frequency would differ from the resonance frequency of the transformer by from 2 k. c. to 5 k. c. Under these conditions a phase difference of approximately 180° would exist between the primary and secondary voltage.

Let us assume that with this phase difference, the voltages are such that the voltage applied to the anode 77 by the primary of the transformer is in phase with the voltage applied to this anode by the secondary of the transformer. The voltages applied to this anode will then add and if they are equal the anode signal potential will then be twice the value obtained when only the secondary voltage is applied to the double diode. This will cause a corresponding increase in the rectified current flowing through resistor 82. On the other hand the signal potentials applied to the anode 78 will be 180° out of phase and if they are equal in magnitude, the sum of the voltages on this anode will be zero. Therefore, no current will flow through resistor 83 and consequently no drop in potential will occur across this resistor.

Since considerable current flows through resistor 82, a relatively large voltage will be developed across this resistor and this voltage will appear between the terminals 89 and 90. Since the current causing this drop in potential must flow through the circuit comprising the resistor 82 and the anode 77 and cathode 80, the direction of the current will be such that the terminal 89 will be negative with respect to terminal 90.

If the frequency of the signal applied to the transformer feeding the double diode is changed so that it just falls within the other side of the transformer frequency response characteristic,

the phase relation between the primary and secondary voltages will shift by approximately 180° . Under this condition, the large signal potential will be applied to the anode 78 while the signal potential on the anode 77 will be substantially zero. Considerable rectified current will now flow through resistor 83 and no current will flow through resistor 82. This current will flow through resistor 83 in such a direction that the resultant drop in potential across this resistor causes the terminal 89 to become positive with respect to the terminal 90.

Thus, as the frequency of the signal applied to the transformer is varied through the frequency range corresponding to the transformer's frequency response characteristic the potential across the terminals 89 and 90 will decrease from a given value, pass through zero, change polarity, and increase to the initial value again. This change in potential across terminals 89 and 90 as the frequency of the signal applied to the transformer is varied may be understood more clearly by reference to Fig. 5. In this figure the curve 101 is the frequency response characteristic of the coupled tuned circuit transformer used to feed the double diode rectifier. The curve designated 106, 102, 104, 108 shows the variation in the voltage between terminals 79 and 80 as the frequency of the applied signal is varied across the frequency response characteristics of the transformer. The large change in control potential made available for a small change in frequency is quite apparent from this curve. As previously stated, this control potential can be utilized in any desired manner.

From the foregoing description, it will be obvious that in a control system which employs a phase discriminating network as shown, a change in either the frequency of a received signal or a change in the tuning of the receiver is converted into a difference in phase between two voltages which are then applied to the phase discriminating network. By utilizing the voltages which may appear across the primary and secondary of a coupled tuned circuit transformer, I have provided in one embodiment of my invention, a simple arrangement for converting a change in tuning from resonance, or a change in the frequency of a received signal, into a change in the phase relation between two alternating current voltages having the same frequency. I have likewise disclosed means for deriving control potentials from said change in phase relation.

While the invention has been shown and described as applied to radio signal receiving circuits, it should be understood that this is for purposes of illustration and should not be taken as a limitation in the application thereof to other circuits for control purposes in response to applied signals.

For example, I contemplate other uses, including the control of circuits operating at frequencies as used in power circuits, at audio frequencies, in synchronizing generators for television and the like, as well as for other purposes hereinbefore mentioned.

I claim as my invention:

1. A signal responsive control system comprising in combination, means including two signal conveying circuits in cascade tuned to resonance at the same frequency and providing two signal potentials having at all times the same frequency and a predetermined normal phase relation, said means being thereby responsive to a change in the frequency of said potentials to change said phase relation, and means connected with each of said circuits for converting a change in said phase relation into a variable controlling potential.
2. In a radio signal receiving system, the combination of means providing two substantially equal signal potentials in response to a received signal, said potentials having the same frequency and a predetermined phase relation to each other when said receiving system is adjusted to resonance with said received signal, means for converting a variation in frequency of said received signal into a variation in phase between said potentials, said first and second named means including the primary and secondary of a coupled tuned circuit transformer through which said received signal is conveyed, means for converting a variation in phase between said potentials into a controlling potential, said means including a double diode rectifier device having a pair of anodes one connected with each of the terminals of the said secondary, a cathode connected through said primary with the secondary, and a resistor network in the secondary providing a center tap for said last named connection, and a control circuit for said system connected with said resistor network to derive said controlling potential therefrom.
3. In a signalling system, the combination of a tunable signal circuit, means for deriving two signal potentials from said circuit in response to an applied signal, means for converting a change in the frequency of the applied signal into a change in phase between said signal potentials, said first and second named means including a pair of tuned interstage coupling circuits arranged in cascade in said system, and connected with said signal circuit, means connected with said circuits for deriving a controlling potential therefrom responsive to said change in phase between said signal potentials, and means for applying at least a portion of said controlling potential to said system to control a condition of operation thereof.
4. In a high frequency signal control system, the combination of means providing a signal source tunable to a predetermined frequency, at least two resonant circuits coupled to each other and arranged in cascade, the first of said circuits being coupled to said signal source to receive energy therefrom, each of said resonant circuits being tuned to the same predetermined frequency, whereby, at resonance, potentials across said circuits differing 90° in phase are provided, and control means responsive to a phase angle change between said potentials when a signal from the source tends to depart from resonance with said coupled circuits.
5. In a signaling system, the combination of means providing a signal source tunable to a predetermined frequency, a frequency variation response network coupled thereto, including two signal circuits in cascade tuned to the same predetermined frequency and so coupled in the system that a predetermined phase angle exists between potentials established therein in response to an applied signal, means for applying an input signal to the first of said signal circuits, said network being responsive to variations in the tuning response of said system and variations in the frequency of an applied signal to cause a change in the phase angle between said potentials, means for rectifying said potentials, and means for deriving from said rectify-

ing means a differential controlling potential for said system.

6. A high frequency control system comprising in combination, a frequency discriminating network comprising primary and secondary resonant circuits tuned to a common operating frequency, said primary and secondary circuits being so related that vector sum potentials of the primary and secondary voltages are provided, said potentials varying in magnitude with variations in the frequency of an applied signal above and below the common resonant frequency of said primary and secondary circuits, rectifier means connected with said primary and secondary circuits for rectifying said sum potentials, and means for deriving direct current potentials therefrom which add in opposition at resonance to provide a substantially zero controlling potential and having a polarity and magnitude above and below resonance dependent upon the direction and degree of departure of an applied signal from the resonance frequency of said circuits.

7. A high frequency control system comprising in combination, means providing two tuned coupled high frequency signal circuits, one of said circuits providing a divided secondary winding having two sections, output resistor means connected between said sections and having a center tap thereon, diode rectifier means having a pair of anodes connected with the terminals of said last named circuit and having a cathode connected to said center tap, said cathode being coupled to the other of said circuits and the relation of said circuits being such that direct current voltages introduced by said tuned circuits through said resistor elements have a phase difference of substantially 90° at the resonance frequency of said circuits, means for tuning said circuits to said resonance frequency, and means for deriving a control potential from the terminals of the output resistor means.

8. In a superheterodyne receiver, the combination with tuning means therefor, of an intermediate frequency amplifier, a coupling transformer for said amplifier having a primary winding and a secondary winding, said secondary winding having two sections, a resistor element having a center tap connected between said sections, a rectifier device having a cathode and two anode electrodes associated therewith, said anode electrodes being connected with the terminals of said secondary winding and said cathode being coupled to the primary winding and conductively connected with said center tap, and

means providing a circuit connection for deriving a differential direct current potential from said resistor element in response to received signals.

9. In a radio signal transmission system for radio receiving apparatus and the like, the combination of means providing two resonant circuits arranged in cascade relation to each other in said system, one of said circuits being coupled to receive a carrier wave and each of said resonant circuits being tuned to said carrier wave, means including said circuits providing a phase discriminating network, means including a rectifier device for deriving a differential controlling potential from said network which varies in polarity and magnitude with the difference in phase between the potentials existing in said two resonant circuits, and means for applying said controlling potential to the system to control a condition of operation thereof.

10. In combination, a source of electric waves of a predetermined operating frequency, at least two resonant circuits coupled to each other and arranged in cascade, the first of said circuits being coupled to said wave source to receive waves therefrom, each of said resonant circuits being tuned to the said operating frequency, the potentials across said coupled resonant circuits differing 90° in phase when the waves impressed thereon are of the said operating frequency, and means responsive to a phase angle change between said potentials when the applied waves depart from resonance with said coupled circuits to provide a differential control potential which varies in magnitude and polarity with degree of departure from and on either side of resonance.

11. In a radio receiving system, tuning indication means therefor comprising in combination, an intermediate frequency amplifier coupling transformer, means for tuning the primary and secondary of said transformer to the same intermediate frequency, a phase discriminating network including said tuned primary and secondary circuits for deriving a direct current controlling potential therefrom which varies in accordance with variations of a received signal from the resonance frequency of said tuned coupled circuits, and means in said network, responsive to the difference in phase between the primary and secondary voltages for producing a differential direct current potential having a magnitude and polarity determined by said phase difference, and a polarized indicating means responsive to said differential potential.

GEORGE L. BEERS.
